UNITED STATES PATENT OFFICE.

ZEPHIR REGNIEE, OF KANKAKEE, ILLINOIS.

SMOKE CONSUMER.

Application filed August 12, 1925. Serial No. 49,788.

My invention relates to means for overcoming the emission of dense smoke from steam boiler furnaces and has for its object the provision of novel means whereby the unconsumed carbon and volatile matters will be removed from the smoke and returned to the fire chamber of the furnace to be consumed. Another object of the invention is to provide means whereby the draft through the furnace may be easily controlled, and other objects of the invention will appear incidentally in the course of the following description. One embodiment of the invention is illustrated in the accompanying drawings and will be hereinafter fully described, the novel features being particularly pointed out in the appended claims.

In the drawings:

- 20 Figure 1 is a front elevation, partly broken away, of an apparatus constructed in accordance with my invention;
 Fig. 2 is a side elevation;
 Fig. 3 is an enlarged sectional elevation
 25 on the line 3—3 of Fig. 2.
 In the drawings, the reference numeral 1 indicates the walls of a steam boiler furnace, and 2 indicates the boiler arranged in the upper portion of the structure, while 3 indicates the furnace having a fire-box or chamber controlled by the fuel doors 4 and an ash pit to which access may be had through the doors 5. A smoke flue 6 rises from the top of the furnace and communicates directly with a laterally extending flue 7 which merges into a vertically disposed branch 8 leading directly to the stack. Above the laterally extending flue 7, I arrange the upper smoke chamber 9 and the lower smoke chamber 10, the former communicating through a pipe 11 with the stack and access to the latter being had through a pipe 12. A damper 13 is interposed in the stack adjacent the outlet pipe 11 and the pivot or shaft of this damper has secured upon one end a lever 14 which carries a weight 15 at its outer end and has an operating rope 16 secured to its inner end. Obviously, the weight 15 tends to hold the damper in the closed position illustrated in the drawings, and by pulling upon the rope the damper may be swung to open position, as will be readily understood. The rope may hang free or it may be secured to a shelf 17

mounted upon the wall of the furnace room 55 or upon any convenient fixed support, a motor 18 being also carried by the said shelf. Immediately below the damper 13, a branch pipe 19 extends to a blower casing 20 in which is mounted a fan or rotary 60 blower having a pulley 21 upon one end of its shaft, which pulley is connected with the shaft of the motor 18 by a belt 22. The pipe 12 constitutes the outlet from the blower casing 20 and establishes communication between the same and the lower smoke chamber 10. The motor 18 is electrically driven, the current being supplied over conductors 23 leading from a local generator or a central plant to and through a switch box 25 70 which is located adjacent the motor.

The water for supplying the boiler flows through a supply pipe 26 which is connected with the city main or other source of supply, a branch 27 leading downwardly from the 75 main supply pipe 26 into the inlet pipe 28 which extends directly to the inlet port of a pump 29 which may be of any preferred form. The outlet pipe 30 of the pump leads directly into the boiler and a cut-off valve 80 31 of any known or preferred construction is interposed in the branch 27 so that, when the required amount of water has been supplied to the boiler, further inflow may be cut off. A branch 32 leads from the main 85 water supply pipe 26 to an automatic regulating valve 33 and from the said valve a pipe 34 is carried into the upper portion of the lower smoke chamber 10 at that end of the same remote from the blower. The said 90 pipe 34 has a portion 35 extending longitudinally through the smoke chamber 10 at the top of the same, and this portion is provided with perforations or jets in its under side through which a spray of water may escape 95 into the smoke chamber, as will be readily understood. The end of the spray pipe 35 nearer the blower is coupled to a short vertical pipe 36 which establishes communication with a second spray pipe 37 extending 100 longitudinally in the upper smoke chamber 9 near the top thereof and having its inner end closed by a cap or other device 38. Upon reference to Fig. 2, it will be noted that I have shown a pair of parallel spray pipes 105 having their ends connected by a closed coupling. A horizontal partition or baffle 39 separates the upper and lower smoke cham-

bers and terminates short of that end of said chambers more remote from the blower so that communication is established between the two chambers, and at the latter end of 5 the upper smoke chamber is a manhole 40 through which access may be had thereto when it is necessary to clean the same. From the lower portion of the lower smoke chamber 10, a return pipe 41 extends downward- 10 ly to a coupling 42 whereby it is connected with the water pipes 27 and 28 so that the warm water which tends to collect in the smoke chamber will be returned to the pump and thence forced into the boiler. From 15 the upper portion of the smoke chamber 10, a gas return pipe 43 extends downwardly and discharges into the furnace adjacent to the grate of the fire box so that the gases may be commingled with the coal or other 20 fuel supplied to the fire box and be burnt, thereby adding to the intensity of the fire while at the same time effecting an economy in the use of the fuel. A second return pipe 25 44, of larger diameter than the return pipe 43, leads from the lower portion of the lower smoke chamber 10 and discharges into the upper portion of the fire box to effect return of the unconsumed particles of carbon to the fire box where they will also be consumed 30 and effect a further economy in the use of fuel.

A shield or deflector 45 is provided in the upper portion of the lower smoke chamber 10 and extends partly through the opening 35 between the two smoke chambers so that the products of combustion flowing through the lower smoke chamber will be prevented from passing directly into the upper smoke chamber and will be forced to flow under the said 40 deflector and around the end of the same in order to enter the upper smoke chamber. These products of combustion will be thereby directed toward the inlet of the gas return pipe 43 and in order that the flow of the 45 gases into said pipe may be complete a guard 46 is provided immediately above the end of the said return pipe, and this guard extends downwardly and inwardly so as to to check the upward flow of the gases at this 50 point. Immediately adjacent the entrance end of the return pipe 44, a brush 47 is mounted in the lower smoke chamber and a guard or deflector 48 is provided to extend from the end of the chamber over the said 55 brush, as shown. A belt 49 connects the shaft of the brush 47 with the shaft of the blower so that this brush as well as the blower will be driven from the motor 18. A guard or deflector 50 extends from the end 60 wall of the smoke chamber below the carbon return pipe 44 and over the entrance to the water return pipe 41, the lower edge of the deflector 50 being normally partly submerged so that it prevents the soot and other 65 particles floating on the water from entering

the water pipe. The rotation of the brush, which consists of a copper core and stiff copper bristles, sweeps the solid particles into the carbon return pipe 44. The draft through the gas return pipe 43 is greater than the natural draft through the upper smoke chamber so that the gas is drawn into said pipe and returned to the furnace, being delivered below the grate.

The stem 51 of the valve 33 extends 75 through the bottom of the valve casing 52 and is connected to a governor lever 53 which is fulcrumed on a bracket 54 on top of the furnace. A weight 55 is adjustably mounted on the free end of the lever and the opposite end of the lever is connected by a link 56 with a piston 57 working in a cylinder 58 in the top of the boiler and exposed to the pressure of the steam therein. A spring 59 is arranged between the valve casing 52 and the lever 53 and tends to hold the valve 33 seated. When the steam pressure in the boiler is low, the valve 33 is seated and there is no diversion of water from the supply pipe into the smoke chambers 9 and 10, but as the steam pressure rises it acts upon the piston 57 and eventually lifts the piston and thereby actuates the lever to unseat the valve and admit water to the spray pipes 35 and 37. The lever may be provided at its fulcrum with a rheostat arm 60 controlling the circuit through the motor 18. The rheostat is illustrated in a more or less conventional manner and may be of any well-known form. When the steam pressure is low and the valve 33 seated, the motor will be driven at high speed to create a strong suction through the gas pipe 43 and the soot pipe 44, but as the steam pressure rises the speed of the motor 100 will be automatically decreased.

The damper 13 is maintained in its closed position at all times, unless there should be a failure of the power for driving the motor so that the circulation of the 110 outflowing smoke and other products of combustion will be through the blower into the pipe 12 and then through the smoke chambers and the pipe 11 into the stack 115 above the damper, as indicated by the arrows in the drawings. The water will escape through the spray pipes 35 and 37 onto the smoke and unconsumed matters flowing through the smoke chambers so that the 120 gases will be cooled and the carbon and other solid particles will be precipitated to the bottom of the respective smoke chambers. The greater portions of these heavier 125 particles collect in the lower smoke chamber where they will be exposed more directly to the force of the blast from the blower and by the said blast will be driven toward the brush 47 which will sweep them into the return pipe 44. The blast from the blower 130 aided by the natural draft through the fur-

nace will also force the gases tending to collect at the top of the smoke chamber into the return pipe 43, the deflector 45 forcing them to flow down from the chamber 5 in order to clear the deflector, as will be readily understood. The water admitted to the smoke chambers will obviously be raised in temperature so that it will not have a chilling effect on the boiler when it enters 10 the same. The soot and gas, however, will be cooled in the smoke chambers and, consequently, they will tend to cool the grates and retard the burning out of the same although they will feed the fire and add to the 15 intensity of the same.

Should the electric current fail so that the motor could not operate, it would be necessary to open the damper 13 and depend upon the natural draft through the smoke 20 stack, but under normal conditions the forced draft from the motor is available and low grade fuel may be used to quickly generate steam without the admission of any dense smoke from the chimney.

25 Having thus described the invention, I claim:

1. In an apparatus for the purpose set forth, the combination of a furnace, a smoke stack leading from the furnace, a damper 30 within the smoke stack, an upper smoke chamber in communication with the stack above the damper, a blower in communication with the stack below the damper, a lower smoke chamber in communication at 35 one end with the blower and at its opposite end with the upper smoke chamber, means within the smoke chambers for removing from products of combustion therein unconsumed gases and solid particles, and means for returning to the furnace unconsumed 40 gases and solid matters from the smoke chambers.

2. In an apparatus for the purpose set forth, the combination of a furnace, a smoke 45 stack leading therefrom, a damper therein, a smoke chamber in communication with the stack above the damper, means below the damper whereby the products of combustion may be permitted to flow out through the smoke stack or be diverted into and driven 50 through the smoke chamber, means within the smoke chamber for removing from the products of combustion unconsumed gases and solid particles, and means for returning 55 to the furnace the said gases and unconsumed particles.

3. In an apparatus for the purpose set forth, the combination of a furnace, a smoke stack leading therefrom, a smoke 60 chamber in direct communication with the smoke stack, means whereby the products of combustion may be caused to circulate through the smoke chamber or permitted to flow directly through the stack, a spray pipe 65 within the smoke chamber, and means for

returning to the furnace the unconsumed gases and solid particles collecting in the smoke chamber.

4. In an apparatus for the purpose set forth, the combination of a furnace, a smoke 70 stack leading therefrom, upper and lower smoke chambers in communication with the smoke stack and each other, spray pipes in the upper portions of the smoke chambers, return pipes leading from the lower smoke 75 chamber to the furnace whereby to return to the furnace unconsumed gases and solid particles, and a brush operating within the lower smoke chamber adjacent the entrance to one of said return pipes. 80

5. In an apparatus for the purpose set forth, the combination of a furnace, a smoke stack leading therefrom, upper and lower smoke chambers in communication with each other and the smoke stack, means 85 whereby products of combustion may be caused to flow directly through the stack or be diverted through the smoke chambers, a deflector mounted in the upper portion of the lower smoke chamber and extending 90 partly into the upper smoke chamber, means for collecting unconsumed gases and solid particles from the products of combustion within the smoke chambers, and means for returning from the smoke chambers to the 95 furnace the unconsumed gases and solid particles.

6. In an apparatus for the purpose set forth, the combination of a furnace, a smoke stack leading therefrom, smoke chambers, 100 means whereby the products of combustion may be permitted to flow directly through the smoke stack or be diverted through the smoke chambers and escape therefrom through the smoke stack, a gas return pipe 105 leading from the smoke chambers to the furnace, and a guard within a smoke chamber extending over the entrance end of said return pipe.

7. In an apparatus for the purpose set 110 forth, the combination of a furnace, a smoke stack leading therefrom, smoke chambers, means whereby the products of combustion may be permitted to flow directly through the smoke stack or be diverted through the 115 smoke chambers, a return pipe leading from the smoke chambers to the furnace whereby to return to the furnace the unconsumed solid particles from the products of combustion, a brush operating adjacent the entrance end of said return pipe, and a guard 120 extending over said brush.

8. In an apparatus for the purpose set forth, the combination with a steam boiler furnace, of a smoke stack leading therefrom, a smoke chamber in communication with the smoke stack, means whereby products of combustion may be permitting to flow directly through the smoke stack or be diverted through the smoke chamber to es- 125 130

- cape therefrom into the smoke stack, means 20
for admitting water to the smoke chamber
for spraying the products of combustion
therein, means for returning to the furnace
5 the gases and solid particles separated by
the water in the smoke chamber, and means
for conveying water from the smoke chamber
to the boiler space of the furnace.
9. In an apparatus for the purpose set 25
forth, the combination with a steam boiler
furnace, of a smoke stack leading there-
from, a smoke chamber in communication
with the smoke stack, means controlled by
the steam pressure in the boiler of the fur-
nace for admitting water to the smoke 30
chamber for spraying the products of com-
bustion therein, means for returning to the
furnace the gases and solid particles sepa-
rated by the water in the smoke chamber,
10
15
20
25
30
35

and means for conveying water from the
smoke chamber to the boiler space of the
furnace.

10. In an apparatus for the purpose set 20
forth, the combination with a steam boiler
furnace, and a smoke stack leading there-
from, of a smoke chamber in communica-
tion with the stack, a blower in communica-
tion with the smoke chamber, means con-
trolled by the steam pressure in the boiler
of the furnace for admitting water to the
smoke chamber and regulating the speed of
the blower, means for conveying water from
the smoke chamber to the boiler space of the
furnace, and means for returning to the
furnace the gases and solid particles sepa-
rated in the smoke chamber.

In testimony whereof I affix my signature.
ZEPHIR REGNIER. [L. S.]
